US00D461778S

(12) **United States Design Patent** (10) Patent No.: **US D461,778 S**
Fox (45) Date of Patent: **** Aug. 20, 2002**

(54) **CO-AXIAL CABLE CONNECTOR**
(75) Inventor: **Michael Fox**, Syracuse, NY (US)
(73) Assignee: **John Mezzalingua Associates, Inc.**,
East Syracuse, NY (US)
(**) Term: **14 Years**
(21) Appl. No.: **29/148,901**
(22) Filed: **Sep. 28, 2001**
(51) LOC (7) Cl. **13-03**
(52) U.S. Cl. **D13/151; D13/133**
(58) Field of Search **D13/133, 151,
D13/154; 439/578, 583, 584; 174/75 C**

Primary Examiner—Joel Sincavage

(74) Attorney, Agent, or Firm—George R. McGuire;
Hancock & Estabrook, LLP(57) **CLAIM**

The ornamental design for a co-axial cable connector, as shown and described.

DESCRIPTION

FIG. 1 is a perspective view of a new and ornamental design for a co-axial cable connector in its closed position, the internal details thereof being illustrated in phantom for environmental purposes only and form no part of the claimed design;

FIG. 2 is a side elevational view thereof;

FIG. 3 is a nut end view thereof;

FIG. 4 is a cable end view thereof; and,

FIG. 5 is a perspective view of the co-axial cable connector in its open position.
